CARTON FLAP RETAINER

Paul Branson, 2302 N. Lynhurst Drive, Apt. A,
Indianapolis, Ind. 46224

Filed Feb. 4, 1969, Ser. No. 15,620

Term of patent 14 years

Int. Cl. D8—03; D15—07

U.S. Cl. D8—259

Fig. 1.

Fig. 2.

Fig. 3

Fig. 4.

FIG. 1 is an elevational view of a carton flap retainer showing my new design.

FIG. 2 is a right-hand side elevational view thereof.

FIG. 3 is a top plan view thereof.

FIG. 4 is a bottom plan view thereof.

The left-hand side elevational view is a mirror image of the right-hand side elevational view of FIG. 2.

I claim:

The ornamental design for a carton flap retainer, substantially as shown and described.
